REFLECTOR

Wallace A. Stanley, P.O. Box 184, Birmingham, Mich.

Filed June 9, 1958, Ser. No. 51,263

Term of patent 14 years

(Cl. D72—1)

FIGURE 1 is a side elevational view of a reflector embodying my new design with the standard shown broken away in part to indicate indeterminate length.

FIGURE 2 is a sectional view taken along the lines 2—2 of FIGURE 1.

FIGURE 3 is an enlarged fragmentary view of the lower left corner of the central bottom full-line panel of FIG. 1, it being understood that the faceted area is continuous throughout the panel and that all the panels are substantially the same.

FIGURE 4 is an enlarged fragmentary sectional view taken along the line 4—4 in FIG. 1.

The dominant features of my design reside in the portions shown in full lines.

I claim:

The ornamental design for a reflector, substantially as shown and described.
